UNITED STATES PATENT OFFICE.

MAHLON E. LAYNE, OF LOS ANGELES, CALIFORNIA.

WELL MECHANISM.

Application filed September 8, 1920. Serial No. 406,846.

To all whom it may concern:

Be it known that I, MAHLON E. LAYNE, a citizen of the United States, residing at Los Angeles, in the county of Los Angeles and State of California, have invented certain new and useful Improvements in Well Mechanism, of which the following is a specification.

The invention relates to well mechanism and particularly to the oiling means for lubricating the sleeve bearing at the neck of a centrifugal or rotary pump and the bearings in the shaft protecting casing extending upwardly from the pump neck. The invention has for its primary objects, the provision of an improved arrangement whereby, (1) the use of the stuffing box at the upper end of the shaft casing is dispensed with together with the expense and care incident to the maintenance of such stuffing box, (2) the loss of oil is reduced to a minimum, such oil being fed into the pump dome at the bottom of the shaft casing and discharging at the top, instead of the reverse arrangement commonly used where the oil is fed into the top of the casing and discharges into the water of the well at the bottom resulting in a loss of oil and a contamination of the water, and (3) a separation of any sand in the water which reaches the sleeve bearing in the pump neck is secured. One embodiment of the invention is illustrated in the accompanying drawings wherein—

Figure 1 is an assembly view showing a pump in vertical section with the improvement applied thereto; Fig. 2 is a transverse section on the line II—II of Fig. 1. And Fig. 3 is a vertical section on a reduced scale through the oil feeding device.

It has heretofore been the practice to lubricate the bearings in the shaft casing of a pump of the general type herein illustrated and the bearing at the pump neck by forcing oil into the top of the shaft casing, such oil being circulated downwardly through the shaft casing past the various bearings in such casing and past the bearing at the pump neck, after which the oil discharges into the water of the well at the pump. The oil which is fed into the shaft casing at the top must necessarily be forced in under considerable pressure, especially in deep well work in order to insure a proper feed downward through the casing and in order to counter-balance the pressure of the water at the pump which tends to carry the water up-

ward through the bearings. This method of applying the oil or the lubricating fluid has the disadvantage that the oil discharged into the water at the pump is wasted and contaminates the water to a certain extent, this latter point being particularly objectionable when the water is designed for certain purposes requiring pure water. A further disadvantage incident to this arrangement is that a stuffing box is required at the upper end of the shaft casing to prevent the oil from working out at this point, and it is a matter of considerable difficulty and expense to keep this stuffing box tight enough to prevent a waste of oil at this point.

The present invention is designed to overcome these difficulties, and briefly stated, involves the use of an improved apparatus for reversing the circulation of oil, the oil being forced into the shaft casing from its lower end and circulating upward past the bearing in the pump neck and past the series of bearings in the shaft casing and discharging at the top of the casing. This oil which discharges at the top of the casing is caught any may be re-used so that the amount of oil required is reduced to a minimum and the water discharged from the pump is substantially free from oil. The oil that is supplied to the bottom of the shaft casing is fed into a separation chamber which surrounds the bearing in the pump and is so arranged that in case of a leakage of water into the separation chamber, a settling or separation of any sand carried thereby may be effected below the point at which the oil or mixture of oil and water secures access to the bearing which is to be lubricated, the construction differing in this feature of oil storage and separation adjacent the bearing from structures heretofore used in which oil was forced in at the pump bearing. The arrangement is also preferably such that the supply of oil is furnished to the upper portion of the sleeve bearing in the pump neck thus counter-balancing any water pressure at the lower end of the bearing and preventing circulation of water upward from the lower end of the bearing. The arrangement and its advantages will be readily understood upon a consideration of the structure as hereinafter described and as illustrated in the drawings.

Referring now to the drawings, the principal parts may be enumerated as follows. 1 is the pump casing which may be of any

approved type and which carries the impellers 2 secured to the shaft 3; 4 is the shaft casing extending upward from the upper portion of the pump (commonly referred to 5 as the pump neck); 5 are a series of bearings in the shaft casing; 6 is a sleeve bearing located at the pump neck; 7 is an oil or separation chamber located in the pump casing surrounding the sleeve bearing and 10 supplied with oil through the pipe 8; 9 is the discharge casing leading to the surface of the ground and discharging through the outlet 10; 11 is the casing of the presser or oil feed device located at the surface of the 15 ground adjacent the upper end of the shaft casing; 12 is the pulley by means of which power is applied to the pump shaft; and 13 is the well casing.

The pump casing in which the oil or separation chamber is located is provided with a plurality of webs 14 (Fig. 3) for giving the necessary strength but the cavities are all freely connected by the passages 15 and 16 and the upper portion of the chamber 25 has free communication with the bearing surface between the bearing and the shaft by reason of the plurality of perforations 17. The lower end of the bearing 6 is exposed to pressure from the chamber and accessible 30 to certain amount of water and perhaps a slight amount of sand carried thereby which gets past the runners 2 and into the bottom of the chamber, but there will be no upward circulation along the shaft tending to carry 35 the sand or dirt since the pressure at the bottom of the bearing is counter-balanced by the pressure applied through the perforations 17. Since the chamber 7 is of considerable volume and the openings 17 are adjacent the upper end thereof, the sand or 40 dirt which gets into the chamber will settle out and, therefore, not reach the openings 17 even tho there is a certain amount of agitation in this chamber incident to the rotation of the impellers in the bottom thereof. Furthermore, the oil being lighter than the water, will tend to fill the space at the top of the chamber, the lower portion of the chamber being occupied by any water which 45 50 may leak into it. The oil which is forced upward between the shaft and the bearing 6 passes into shaft casing 4 and rises through such shaft casing past the various bearings 5 and finally escapes into the receptacle 18 (Fig. 1) which surrounds the shaft above the bearing 19. From this receptacle the oil 55 may be carried through a suitable pipe 20 to a reservoir (not shown) and may be subsequently re-used.

60 The device for forcing the oil downward through the oil pipe 8 is shown in Fig. 3 and comprises the casing 11 having a cylinder 21 at its lower portion and a cylinder 22 at its upper portion. A piston 23 is carried in the lower cylinder and a piston 24

in the upper cylinder, such pistons being connected by the piston rod 25. The upper cylinder above the piston is filled with oil and such oil is conducted by means of the pipe 26 to the upper end of the pipe 8. 70 Pressure is applied to the piston 23 upward from the pipe 27 communicating with the upper end of the discharge casing 9. A drain pipe 28 communicating with the chamber above the piston 23 serves to permit of the escape of any water which may leak past the piston from the lower to the upper side.

Since the piston 23 is larger than the piston 24 sufficient pressure will be applied by 80 the water from the discharge casing to overcome any head in the oil chamber 7 and feed the oil from such chamber upward to the receptacle 18 in the upper end of the shaft casing. The application of the feed 85 is also automatic since the pressure in the cylinder 21 is released when the pump stops, thus stopping the flow of water through the discharge casing. Various other means might, of course, be provided for giving the 90 necessary feed downward through pipe 8 and the invention is not limited in this particular. The shape and location of the oil and separation chamber might also be considerably changed or modified depending 95 upon conditions. If desired a considerable amount of water may be allowed to mix with the oil in the separation chamber since this water will be free from sand and dirt due to the separation functions of the chamber. 100

What I claim is:

1. In combination in a well mechanism a centrifugal or rotary pump provided with an oil reservoir adjacent the pump neck and with impellers, and upwardly extending discharge casing, a shaft casing extending upwardly from the pump neck, a shaft connected to the impellers and extending upward through the shaft casing, a bearing at the pump neck extending into said oil reservoir, and means for forcing oil into said reservoir and thence upward through the shaft casing. 105

2. In combination in a well mechanism a centrifugal or rotary pump provided with an oil reservoir adjacent the pump neck and with impellers, an upwardly extending discharge casing, a shaft casing extending upwardly from the pump neck, and provided with a series of bearings for the shaft, a shaft connected to the impellers and extending upward through the shaft casing and the bearings therein, a bearing at the pump neck extending into said oil reservoir, and means for forcing oil into said reservoir and thence upward through the bearing at the pump neck and past the series of bearings in the shaft casing. 110

3. In combination in a well mechanism a centrifugal or rotary pump provided with 115

- an oil reservoir adjacent the pump neck and with impellers, an upwardly extending discharge casing, a shaft casing extending upwardly from the pump neck, a shaft connected to the impellers and extending upward through the shaft casing, a bearing at the pump neck extending into said oil reservoir and provided with a perforation adjacent the upper portion of the reservoir to permit the passage of oil to the shaft and prevent a circulation of liquid upward along the shaft from the lower end of the bearing, and means for forcing oil into said reservoir and thence upwardly through the shaft casing.
4. In combination in a well mechanism, a centrifugal or rotary pump provided with a closed separating reservoir in the upper portion of its casing, an upwardly extending shaft casing, a drive shaft therein extending down into the pump casing, a bearing in the upper portion of the pump casing lying partially in said separating reservoir, an opening through the bearing above its lower end and communicating with the upper portion of said reservoir and means for applying a lubricating fluid under pressure to said reservoir to cause the circulation thereof through said opening in the bearing and upward into the shaft casing.
5. In combination in a well mechanism a centrifugal or rotary pump provided with an oil reservoir adjacent the pump neck and with impellers, an upwardly extending discharge casing, a shaft casing extending upwardly from the pump neck, a shaft connected to the impellers and extending upward through the shaft casing, a bearing at the pump neck extending into said oil reservoir, and means for applying pressure from the discharge casing to force oil downward to the oil reservoir and thence upward into the shaft casing.
6. In combination in a well mechanism a centrifugal or rotary pump provided with an oil reservoir adjacent the pump neck and with impellers, an upwardly extending discharge casing, a shaft casing extending upwardly from the pump neck, a shaft connected to the impellers and extending upward through the shaft casing, a bearing at the pump neck extending into said oil reservoir, and means for applying pressure from the discharge casing to force oil downward to the oil reservoir and thence upward into the shaft casing; and thence past the bearings in the shaft casing.
7. In combination in a well mechanism a centrifugal or rotary pump provided with an oil reservoir adjacent the pump neck and with impellers, an upwardly extending discharge casing, a shaft casing extending upwardly from the pump neck, a shaft con-
- nected to the impellers and extending upward through the shaft casing, a bearing at the pump neck extending into said oil reservoir, means for forcing oil downward from the surface of the ground to said oil reservoir and thence upwardly through the shaft casing, and means for collecting the oil for re-use at the upper end of the shaft casing.
8. In combination in a well mechanism, a centrifugal or rotary pump provided with impellers, a shaft casing extending upwardly from the pump, bearings for supporting the shaft, a separation chamber adjacent the lower portion of the shaft casing, and means for forcing oil into the chamber and upward into the shaft casing.
9. In combination in a well mechanism, a centrifugal or rotary pump provided with impellers, a shaft casing extending upwardly from the pump, bearings for supporting the shaft, a separation chamber adjacent the lower portion of the shaft casing, and means for forcing oil into the chamber and upward into the shaft casing, past the bearings in such casing.
10. In combination in a well mechanism, a centrifugal or rotary pump provided with impellers, a shaft casing extending upwardly from the pump, bearings for supporting the shaft, a separation chamber adjacent the lower portion of the shaft casing, and means for forcing oil into the chamber and upward into the shaft casing, past the bearings in such casing, and out at the upper portion of said casing.
11. In combination in a well mechanism, a centrifugal or rotary pump, a discharge casing extending upwardly from the pump, a vertical drive shaft for the pump, a bearing for the shaft in the pump, a shaft casing surrounding the shaft, an oil chamber, piping leading therefrom to the pump bearing, a piston in the oil chamber and means for applying pressure from the discharge casing to cause said piston to force oil from said chamber to said bearing.
12. In combination in a well mechanism, a centrifugal or rotary pump, a discharge casing extending upwardly from the pump, a vertical drive shaft for the pump, a bearing for the shaft in the pump, a shaft casing surrounding the shaft, an oil chamber, piping leading therefrom to the pump bearing, a differential piston device in the oil chamber having two piston members of different diameter, and means for applying pressure from the shaft casing to the larger piston member to cause said member to move the smaller piston member against a body of oil in the chamber and feed it to said bearing.
